UNITED STATES PATENT OFFICE.

JOHN B. FRECHETTE, OF VALPARAISO, INDIANA.

FLEXIBLE AND RESILIENT SHOE-SOLE.

1,348,706.

Specification of Letters Patent.

Patented Aug. 3, 1920.

Application filed December 11, 1919. Serial No. 344,066.

To all whom it may concern:

Be it known that I, JOHN B. FRECHETTE, a citizen of the United States, residing at Valparaiso, in the county of Porter and 5 State of Indiana, have invented certain new and useful Improvements in Flexible and Resilient Shoe-Soles, of which the following is a specification.

This invention relates to improvements in 10 soles for boots and shoes and is particularly designed to relieve the jar coincident with walking and to prevent the penetration of moisture to the interior of the boot or shoe through the sole.

15 The principal objects of the invention are: to provide means for cushioning or effecting resiliency of the sole of a boot or shoe without materially increasing its weight; to provide means for rendering the 20 sole impervious to moisture; and to effect the two above mentioned objects without decreasing the pleasing appearance or wearing qualities of the shoe or boot as a whole.

Furthermore the invention aims to provide 25 a sole for boots or shoes wherein the structure effecting the above objects is disposed between the outer and inner soles thus presenting the usual durable leather surface to the ground and the necessary smooth 30 seamless surface to the foot.

With these objects in view and others which will appear as the nature of the invention is better understood, the invention comprises the various novel features of construction and arrangement of parts, which 35 will be more fully described hereinafter and set forth with particularity in the claims appended hereto.

Figure 1 is a perspective view of a shoe 40 provided with a sole made in accordance with the embodiments of the present invention, and

Fig. 2 is a view on the line 2—2 of Fig. 1.

In the drawings wherein like characters 45 of reference indicate like or similar parts throughout the several views A designates what is termed the "upper" of the shoe, B the outer sole and C the inner sole, between which the present device generally designated by D is disposed.

The invention *per se* contemplates mounting upon the outer sole B a thin or light leather sole 1 of the same breadth and configuration. Upon this light leather sole 1 is 55 mounted but not positively secured, a layer of sponge-rubber 2 terminating short of

the peripheral edges of the light sole 2 and upon which is mounted, but not positively secured, a smaller cork layer 3 terminating short of the peripheral edges of the rubber 60 layer 2 and having a ribbon of leather 4 extending about the edges thereof. A canvas layer 5 extending over the top of the cork layer 3 and leather ribbon 4 extends about the edges of the ribbon 4 as at 6 and against 65 which the edge 7 of the upper A lies. The inner sole C is mounted upon this canvas cover as shown thus disposing beneath the sole of the foot layers of leather, canvas, cork, rubber and leather to absorb shock 70 and prevent penetration of moisture.

For securing the outer sole B to the upper A two strips,—one of canvas 8 and one of leather 9 are sewed or nailed between a leather retaining band 10 and the outer sole 75 B and extend upwardly and then downwardly about an inner band 11 on the rubber layer 2 to lie against the edge 7 of the upper A.

The edges of the canvas strip 8, leather strip 9, upper A and canvas layer 5 are then 80 stitched to the leather ribbon 4 and inner band 11 in the manner illustrated in Fig. 2.

As the operation and construction of the sole will, it is thought, be obvious from the foregoing description, I merely desire to 85 point out that certain slight changes may be necessitated when the sole is extensively commercialized and permission to make these changes is reserved provided they fall within the scope of what is claimed. 90

What is claimed is:

1. A shoe sole of the type described including an inner and an outer sole, a rubber layer between the inner and outer soles, a cork layer adjacent the rubber layer, a canvas layer adjacent the cork layer, and means secured to the outer sole and the shoe upper for retaining the layers in place.

2. A shoe sole of the type described including an inner and an outer sole, a rubber 10 layer between the inner and outer soles, a cork layer adjacent the rubber layer, a retaining ribbon about the edges of the cork layer, a canvas layer adjacent the cork layer and extending about the retaining ribbon, a 15 portion of the upper lying against the edges of the canvas layer, strips secured to the outer sole and lying against the upper, a retaining band beneath the strips, and means for securing the band, strips, the upper, 20 canvas, and retaining ribbon together to se-

curely hold the shoe sole in assembly for the purpose set forth.

3. A shoe sole of the type described including an inner and an outer sole, a rubber layer between the inner and outer soles, a cork layer above the rubber layer, a canvas layer above the cork layer, and strips secured to the outer sole and the shoe upper for retaining the layers in place.

10 4. A shoe sole of the type described including an inner and an outer sole, a rubber layer between the inner and outer soles of less width than the same, a cork layer on the rubber layer of less width than the rubber layer, a retaining ribbon about the edges of

the cork layer, a canvas layer extending over the cork layer and about the retaining ribbon, the edges of the upper lying against the edges of the canvas layer, strips secured to the outer sole and lying against the edge 20 of the upper, a retaining band beneath the strips, and means for securing the band, strips, edge of the upper, canvas and retaining ribbon together to securely hold the shoe sole in assembly for the purpose set 25 forth.

In testimony whereof I affix my signature hereto.

JOHN B. FRECHETTE.
